CLAIM

The ornamental design for a combined face mask and shield, as shown and described.

DESCRIPTION

FIG. 1 is a perspective view of a combined face mask and shield, showing our new design;

FIG. 2 is a front elevational view thereof;

FIG. 3 is a rear elevational view thereof; and,

FIG. 4 is a right side elevational view thereof, the left side elevational view being a mirror image thereof.

FIG. 1

FIG. 2

FIG. 3

FIG. 4
